UNITED STATES PATENT OFFICE.

SAMUEL K. BEHREND, OF WASHINGTON, DISTRICT OF COLUMBIA, ASSIGNOR
TO HOWARD EVANS, OF PHILADELPHIA, PENNSYLVANIA.

STEEL-CONVERTER.

SPECIFICATION forming part of Letters Patent No. 698,787, dated April 29, 1902.

Application filed July 31, 1900. Serial No. 25,434. (No model.)

To all whom it may concern:

Be it known that I, SAMUEL K. BEHREND, a citizen of the United States of America, residing at Washington, in the District of Columbia, have invented certain new and useful Improvements in Steel-Converters, of which the following is a specification.

My invention relates to an improvement in converters for the manufacture of steel.

Nearly all if not every large machine-shop is equipped with an ordinary iron-foundry for making iron castings in connection with the work on which the tools are doing duty. A large tonnage of iron castings is used where steel castings should be put in; but in consequence of the difficulty of getting steel castings iron is inserted, and necessarily two or three times the weight is added to the objects under manufacture. Under the present methods it is next to impossible to get steel castings except by causing much delay in carrying on the work. Rarely can an order be filled for steel castings at any of the steel-casting plants within thirty days, and more frequently it requires nearer ninety days. Thus it will be seen how greatly the average machine-shop is embarrassed for the want of castings, and for this reason iron is not infrequently employed where steel should be used and is preferred, thereby increasing the weight of the article being manufactured and also increasing the liability of breakage.

My converter remedies the foregoing objections and places an effective steel plant within the grasp of all large machine shops having their own iron-foundries at a comparatively trifling initial cost.

The object of this converter is to provide an equipment for any iron-foundry now in operation using the regular cupola which they already have for melting the charge; and it consists in a ladle which forms the bottom of the converter when in position, which ladle is preferably adapted to run on a suitable track from cupola to converter, and vice versa, in connection with means for raising and lowering the ladle into or out of contact with the upper portion or stack of the converter, as the case may be.

My process can be made continuous, or a single blow can be made, which greatly re-

duces the cost which would naturally be entailed by the use of the open-hearth process, which latter must be made continuous both day and night and requires expert operators, 55 not to speak of long continuous heating, from ten to twelve hours, to complete the melting, and can never be run economically unless the charge runs from ten to twenty tons. With my converter as soon as a blow is made everything can be allowed to cool down and it can be started again at will.

Another desirable use to which my converter can be put is in the manufacture of what is known as "semisteel" or in taking 60 just such foundry-iron as is ordinarily used in making gray-iron castings, as by running this iron into the ladle and giving it, say, a five or ten minute blow a large portion of the carbon is thereby removed, and the result 70 is an iron casting of great toughness and tenacity with a strength nearly equal to that of mild steel, which could be utilized as an excellent metal for car-wheels, or, in fact, for any product where greater strength than cast- 75 iron is required.

In addition to the several features named and the objects attained—such as the construction of the truck with ladle attached and capable of being tilted or lifted into place beneath the stack of the converter to form a part thereof and the adjustable twyers by which any angle of blow can be obtained, either of the whole number of twyers or the different individual twyers—still other features consist of the means of disposing of the slag by means of slag-holes and a number of other more or less important accessories, which will be hereinafter more fully described, and particularly pointed out in the claims.

In the accompanying drawings, Figure 1 is a view in side elevation. Figs. 2 and 3 are vertical sections taken at right angles to each other. Fig. 4 is a plan view. Fig. 5 is a plan view of the ladle. Fig. 6 is a horizontal section on line 22 of Fig. 2. Figs. 7, 8, and 9 are sections and details showing the location and construction of the slag-holes. Fig. 10 is a bottom plan view of the twyer-frame. Fig. 11 is a top plan view of the same, the latter 100 two figures both being on an enlarged scale; and Figs. 12 and 13 are views in section and

elevation of the means for elevating and lowering the ladle of the converter.

A represents a superstructure erected on a suitable foundation—as, for instance, the 5 piers 1 1. The superstructure or framework can of course be variously constructed—as, for instance, it may be entirely built up of I-beams of suitable metal, as is indicated by the parts 2 2 in the drawings.

10 B and C indicate the upper and lower sections of the converter, or, as I shall term them, the “stack” and “ladle,” respectively. The stack B is stationary and is preferably supported by means of the side brackets 3 3 upon 15 the horizontally-disposed side beams of the superstructure. This stack is of the upright cylindrical type, with a tapering chimney at the top, and consists of a sheet-metal shell lined with fire-brick, silica, or other refractory material to a suitable depth, as is customary. This stack is not only open at the top, but also at the bottom, as more fully shown in Fig. 2, where it is constructed and adapted 20 to fit the ladle when the converter is in operation. The stack B is surrounded by the customary wind-belt 4, which latter may be constructed of sheet-metal plates securely bolted and riveted together by means of angle-irons. An inlet 5 is provided for the passage of air for the supply of this wind-belt. In this connection it may be stated that while any form of twyer may be employed in the holes 6 6 provided for them, yet I prefer substantially the form shown and described in 25 my concurrently-pending application, Serial No. 32,805, filed July 31, 1900, which application is a divisional part of this one.

Two or more slag-holes 16 16 are formed in the lower end of the stack B, as is shown more 30 particularly in detail in Figs. 7, 8, and 9 of the drawings. Their location, it will be understood, is just above the surface of the charge, where access to the latter can be easily had at any time during the process of conversion, thus avoiding the necessity of tilting the converter or stopping the blast—in short, rendering it possible to dispose of the slag in the most convenient manner possible and at the same time economically without any interruption of the operation of conversion.

The ladle C is carried upon a truck E. This truck is provided with wheels 18 18, which travel on tracks 20 provided therefor. These tracks 20 of course extend centrally through 35 the framework or superstructure of the converter and may be carried to any suitable point. On the truck are erected a pair of standards 21 21, and trunnions 22 22, projecting in opposite directions from the ladle, 40 are journaled in these standards, where they are held against the possibility of accidental displacement by the cap-plates 23, which are bolted securely to the upper ends of the standards 21 21. An arm 24 projects upwardly 45 from each of these cap-plates in position to enter sockets 25 on the sides of the stack B when the sections are together, thus insuring

perfect alinement and preventing lateral displacement. On each of these trunnions, as a means for tilting the ladle when the charge 70 is to be poured out, the worm-gears 26 26 are secured. Worms 27 on shafts 28 engage the teeth of the worm-gear. The worm-shafts 28 are journaled in the standards 21, as shown in Fig. 1. Both ends of these shafts 28 are 75 preferably square or angular in cross-section to receive a crank or other means by which they are turned, and the operation of tilting the ladle is rendered easy and accurate by turning these shafts 28, and by the use of the 80 worm and worm-gear the ladle is held locked wherever it is set against the possibility of displacement from any accidental disturbance. Spouts 30 30 at either end discharge 85 the molten mass.

As a means for raising and lowering the ladle C some suitable jacking mechanism is provided. I have illustrated a convenient means for accomplishing this, which I will now describe.

A block 31 is constructed and adapted to fit a socket 32, centrally located on the bottom of the truck-frame. A shaft 33, preferably journaled in the track-rails 20, extends centrally through this block 31 and has secured thereon a cam 34, which preferably carries a series of hardened-steel antifriction-rollers 35 on a common spindle 36 in the cam. These rollers 35 are adapted to engage the curved ways 37 on the lower interior surface of the block 31 and by that action, when in the vertical position indicated in Figs. 17 and 18, to hold the block securely in the socket 32 of the truck, the latter, in an elevated position, lifting the wheels 18 from the track-rails 20 105 and forcing the ladle into tight engagement with the stack B. The shaft 33 may be rocked in any convenient manner, and as a convenient means for doing this I have shown a worm-gear segment 39, secured on one end of 110 the shaft. A worm 40 on shaft 41 engages the teeth of the worm-gear segment and turns and locks the shaft in any position required, cranks 42 42 being provided for rotating this shaft in either direction. Obviously this device for raising and lowering the ladle can 115 be replaced by a simple ram operated by hydraulic or other power where such facilities are available.

Having described the preferred details, the 120 operation will be briefly outlined. The ladle C, mounted on the truck provided therefor, is run along the track to such point as may be arranged for charging the ladle, after which it is run back to a point immediately 125 beneath the stack, whereupon it is lifted into engagement therewith, as has been fully described, and the air-blast is turned on and the twyers set to such inclination as is deemed most suitable for the work to be performed. 130 When the operation is complete, the ladle is lowered and carried off on the track to a point arranged for the discharge of the contents. The same or another ladle can be returned

to the stack with a new charge and the process of converting be repeated. In this manner a two-ton charge of metal can be converted into high-grade steel equal to the product of the best open-hearth furnace in about twenty minutes. The process can be made continuous or a single blow can be made, thus greatly reducing the cost. With this converter as soon as a blow is completed, if desired, everything can be allowed to cool down, or it can be started up at will.

It is evident that slight changes other than those heretofore mentioned might be made in the form and arrangement of the several parts described without departing from the spirit and scope of my invention, and hence I do not desire to limit myself to the exact construction herein set forth; but,

Having fully described my invention, what I claim as new, and desire to secure by Letters Patent, is as follows:

1. A converter comprising a stationary stack, and a movable ladle, the ladle adapted to contain the molten metal, and the stack having a series of twyers extending around it, their lower ends extending no lower than the upper end of the ladle whereby the blast of air issuing from the twyers is directed upon the surface of the metal and toward the center thereof.

2. A converter comprising a stack and ladle, one stationary and the other movable, the ladle adapted to contain the molten metal and the stack having a plurality of twyers therein which extend around it at a point at or near its lower end and no lower than the upper edge of the ladle, said twyers vertically adjustable and constructed and adapted to be locked in any of their various adjustments.

3. A converter comprising a stack and ladle, one of which is movable with respect to the other, the stack having twyers located at its lower end, which twyers extend around the converter and are located no lower than the upper edge of the ladle, said twyers being movable at their outer ends from their inner ends as centers and provided with means for locking them in the different adjustments.

4. A converter comprising a stack and ladle, one being stationary and the other movable, the ladle adapted to contain molten metal and the stack having a series of twyers extending entirely around it at a point at or near its lower end, the stack also provided at its lower end with openings for the removal of slag therefrom, the inner ends of the twyers and the slag-openings being in approximately the same horizontal plane.

5. A converter comprising a stack and ladle detachably connected together, a wind-supply and a series of twyers in communication with said wind-supply and extending around the converter with their discharge ends at a level approximately coincident with the joint formed between the stack and ladle.

6. The combination with the stack, of a truck carrying a ladle which latter forms the complement of the stack when in contact therewith, the truck having a centrally-located socket on its lower surface, a block below the socket, said block having curved ways on its lower interior surface, a shaft having a cam, said cam carrying antifriction-rollers adapted to turn in contact with the curved ways on said block, a worm-segment on the shaft and a worm engaging said segment for rocking the shaft whereby to raise or lower the ladle of the converter.

7. The combination with the stack of a converter, of a truck having a ladle thereon, the truck having a centrally-located socket on its lower surface, a vertically-sliding block centrally located beneath the truck and in alignment with the socket when the truck is in position to be raised and lowered, and a rock-shaft having cam mechanism thereon constructed and adapted to raise and lower the block whereby to control the position of the truck.

In testimony whereof I have signed my name to this specification in the presence of two subscribing witnesses.

SAML. K. BEHREND.
